UNITED STATES PATENT OFFICE.

STANLEY NICHOLSON, OF WHITING, INDIANA, ASSIGNOR TO STANDARD OIL COMPANY, OF CHICAGO, ILLINOIS, A CORPORATION OF INDIANA.

DESIGN FOR A CANDLE.

Application filed June 3, 1927. Serial No. 22,304. Term of patent 7 years.

To all whom it may concern:

Be it known that I, STANLEY NICHOLSON, a citizen of the United States, residing at Whiting, county of Lake, and State of Indiana, have invented a new, original, and ornamental Design for a Candle, of which the following is a specification, reference being had to the accompanying drawing, forming a part hereof, in which—

I claim:
The ornamental design for a candle as shown.

STANLEY NICHOLSON.
